E. W. Bentley

UNITED STATES PATENT OFFICE.

LEE P. HYNES, OF ALBANY, NEW YORK, ASSIGNOR TO CONSOLIDATED CAR-HEATING COMPANY, OF ALBANY, NEW YORK, A CORPORATION OF WEST VIRGINIA.

LOAD-OPERATING ARM.

1,333,113.

Specification of Letters Patent.

Patented Mar. 9, 1920.

Application filed October 18, 1918. Serial No. 258,750.

To all whom it may concern:

Be it known that I, LEE P. HYNES, a citizen of the United States, residing at Albany, in the county of Albany and State of New York, have invented certain new and useful Improvements in Load-Operating Arms, the following being a full, clear, and exact disclosure of the one form of my invention which I at present deem preferable.

For a detailed description of the present form of my invention, reference may be had to the following specification and to the accompanying drawing forming a part thereof, wherein—

Figure 1 is a side elevation of my device;

Fig. 2 is a plan thereof;

Fig. 3 is a perspective view partly broken away;

Fig. 4 is a transverse section on the line

4—4 of Fig. 1;

Fig. 5 is a detail, and

Fig. 6 shows the application of my device as a means for enabling a pressure engine to operate a door.

My invention relates to an arm which is adapted to be attached in a radial position to a shaft and to serve as an agent by which the shaft may impart reciprocating motion to a door, gate, valve or similar device which

constitutes the load which the shaft is to operate. It is frequently the case that in such a situation the arm is desirably capable of longitudinal contraction against the force of an expanding spring so that the door or other load can be moved a certain degree independently of the push or pull of the arm upon it. I have incorporated such a feature in my organization.

Referring to the drawing, A represents the fundamental part of the arm which is in the form of a sheath in which telescopes the extension part B that is connected to the door F, or other object by means of a pivot and slide such as is well known.

The sheath part is formed of sheet metal which is bent over at its top and bottom edges as appears in Figs. 3 and 4. The overturned portion forms a tubular casing to contain a helical spring H and it also forms

a channel or guideway in which slides the extension part B. The extreme edges of the sheet metal of which the sheath is formed are turned out to have a resilient bearing on the part B. That part can still slide freely in the sheath but is maintained in place

against the flat portion of the sheath. In each tubular part is a helical spring H and at the rear end a pin K is passed through both tubular parts to form a stop for the rear ends of the springs. At the forward end of the sheath, there are two U-shaped lugs P, P riveted to the part B in line respectively with the ends of the springs, while a pin K¹, similar to K, is passed through the two tubular parts in front of the lugs P, P to serve as a front stop for the part B when pressed by the springs. It is manifest that if the springs are under compression they will abut against the lugs P, P on the extension part B and tend to press it outward or away from the sheath so far as is permitted by the stop-pin K¹. Conversely they will yield and allow the part B to be pushed into the sheath and thereby cause a contraction in length of the arm as a whole. On the back of the sheath is riveted a plate C with a hub D thereon in which is a hexagonal hole to receive one end of the operating shaft. The rivet holes in plate C are countersunk, as shown in Fig. 5, and the corresponding holes in the sheath are punched with a conical flange that enters the countersunk portion of the holes in the plate. By this means a secure torsion-resisting connection between the plate and the sheath is secured while leaving a smooth interior surface inside the sheath against which the part B bears.

The advantages of this construction are that it affords a simple, cheap arrangement that is readily assembled and reassembled to meet different conditions of use. The sheath is of sheet metal easily bent into the form shown, which affords the required strength in both a transverse and lateral direction, while at the same time an appropriate slotted chamber for the spring is afforded together with the guideway for the movement of the sliding part. The said sliding part is merely a length of standard rolled or forged wrought metal as distinguished from a casting, it can be cut of any desired length from stock available in almost any machine shop, and if necessary can be readily given a bend or offset to make it fit the particular job in hand. To take the arm apart it is only necessary to remove the pin K¹.

What I claim as new and desire to secure by Letters Patent is:

1. A load operating arm comprising a

sheet metal sheath part having its edges bent over to form a guideway, and an extension part formed of flat rolled or forged metal, said bent over edges having a resilient bearing upon said extension part.

5. A load-operating arm comprising a sheath part formed of sheet metal bent over at each edge to form a guideway, and a flat rolled or forged extension part contained in said guideway.

10. A load-operating arm comprising a sheath part of sheet metal with its edges bent over to form spring casings, springs in said casings, and a flat extension part engaging the said springs and guided along said sheath part.

15. A load-operating arm comprising a sheath part of sheet metal bent over at its edges to form spring casings and guides, springs in said casings and a flat extension part contained in said guides and engaging said springs.

20. A load-operating arm comprising a sheath part having on each edge a slotted tubular offset and an extension part of flat metal guided to slide along the sheath.

25.

6. A load-operating arm comprising a sheath part having on each edge a slotted tubular offset, springs in said tubular portions, and an extension part of flat metal 30 guided to slide along the sheath and provided with lugs engaging the said springs and movable in the slots of the tubular portions.

7. A load-operating arm comprising a 35 sheath part formed of sheet metal bent over one face at each edge to form a guideway, a shaft receiving device secured to the other face of said sheath, and a flat extension part contained in and projecting from the 40 said guideway.

8. A load operating arm comprising a sheath part formed of sheet metal bent over one face at each edge to form a guideway, means for connecting said sheath part to a 45 shaft extending at a right angle thereto, and a flat extension part contained in and projecting from the said guideway.

Signed at Albany, county of Albany, State of New York, this 15th day of Octo- 50
ber, 1918.

LEE P. HYNES.
